US00D769698S

(12) **United States Design Patent** (10) **Patent No.:** **US D769,698 S**
Oltrogge (45) **Date of Patent:** **** Oct. 25, 2016**

- (54) **FRAMING BRACKET**
(71) Applicant: **John Oltrogge**, Westminster, CO (US)
(72) Inventor: **John Oltrogge**, Westminster, CO (US)
(**) Term: **14 Years**
(21) Appl. No.: **29/522,980**
(22) Filed: **Apr. 6, 2015**

(57) **CLAIM**

The ornamental design of a framing bracket, as substantially shown and described.

DESCRIPTION

FIG. 1 is a perspective view of the framing bracket of the present invention;

FIG. 2 is a right side view of the framing bracket of the present invention, the left side view being a mirror image thereof;

FIG. 3 is a top view of the framing bracket of the present invention, the bottom view being a mirror image thereof;

FIG. 4 is a front view of the framing bracket of the present invention;

FIG. 5 is a rear view of the framing bracket of the present invention; and,

FIG. 6 is a top view of the framing bracket of the present invention prior being bent into its final shape.

1 Claim, 3 Drawing Sheets
